AIRFOIL TIP CONSTRUCTION

Michael Watter and George W. Pancoe, Philadelphia, Pa., assignors to Edward G. Budd Manufacturing Company, Philadelphia, Pa., a corporation of Pennsylvania

Application March 6, 1943, Serial No. 478,234

10 Claims. (Cl. 244—123)

This invention relates to an airfoil structure and particularly to a tip structure adapted to form the tip of a wing, fin, stabilizer or other form of airfoil or similar structure.

An object of this invention is to provide a tip structure for airfoils or the like having an improved arrangement of strain resisting members so constructed as to provide maximum stress resistance with relatively light weight; which can, if desired, be formed entirely of material such as stainless steel; and which forms in effect a structural unit with the associated airfoil or similar structure.

These and other objects which will be apparent are attained by the present invention, one embodiment of which is shown for the purposes of illustration in the accompanying drawings, in which:

Fig. 1 is a view in side elevation of an airfoil tip constructed in accordance with one embodiment of this invention, showing the same employed to form the upper tip of a vertical stabilizer fin having an associated rudder mounted thereon;

Fig. 2 is an enlarged view of the tip structure shown in Fig. 1;

Fig. 3 is a bottom plan view from the line 3—3 of the structure shown in Fig. 2;

Fig. 4 is an enlarged vertical section taken on the line 4—4 of Fig. 2;

Fig. 5 is a side elevation on the same enlarged scale as Fig. 4 of a portion of the tip shown in the broken-line area 5 of Fig. 2;

Figs. 6 and 7 are enlarged partial sectional views on the lines 6—6 and 7—7, respectively, of Fig. 2;

Fig. 8 is an elevation on an enlarged scale of the structure embraced within the broken-line area 8 of Fig. 1 showing the connection at one point between the tip and the main airfoil;

Fig. 9 is a vertical section on the line 9—9 of Fig. 8;

Figs. 10 and 11 are sections on the lines 10—10 and 11—11, respectively, of Fig. 9;

Fig. 12 is an enlarged elevation of a detail, showing one type of a connection between the tip structure and the main airfoil body;

Fig. 13 is a section on the line 13—13 of Fig. 12;

Fig. 14 is an enlarged elevation of the joint comprised within the broken circle 14 on Fig. 2;

Figs. 15, 16 and 17 are sections on the lines 15—15, 16—16, 17—17, respectively, of Fig. 14;

Fig. 18 is a section on the line 18—18 of Fig. 17;

Fig. 19 is a bottom plan view from the line 19—19 of part of the structure shown in Fig. 17;

Fig. 20 is an enlarged side elevation of the joint comprised in the area of the broken circle 20 in Fig. 2;

Fig. 21 is a section on the line 21—21 of Fig. 20;

Fig. 22 is a section on the line 22—22 of Fig. 20;

Fig. 23 is an enlarged section on the line 23—23 of Fig. 2; and,

Fig. 24 is a section on the line 24—24 of Fig. 23.

In the present invention a structure, such as an airfoil, is provided with a tip structure which is secured thereto in such a way as to form an integral part of the airfoil structure. The tip structure embodies a cantilever truss and is mounted on the airfoil so as to project outwardly and to provide a cantilever support over-reaching one edge of the airfoil structure to form a support for such a device as, for example, the upper bearing of an associated rudder shaft. The cantilever truss system of the tip structure is so related to the airfoil body that the main elements of the cantilever truss system are integrally united with the main stress resisting members of the associated airfoil structure, and the joints between the two are constructed and arranged to provide a rugged connection of relatively light weight.

As illustrated in Fig. 1, the invention is shown in connection with such an airfoil structure as, for example, a vertical stabilizer or fin 31 having a forward spar 32 and a rearward or main spar 33, both extending vertically throughout the height of the fin structure. A rudder 34 is mounted for horizontal movement about a rudder shaft 35 hinged at its lower end in a lower extension 36 of the fin structure, at its upper end to the rear portion of the tip to be described herein, and intermediate to hinge connections 37 and 38.

The tip structure 41, Figs. 2 and 3, includes a base frame or bulkhead 42, which extends along substantially the entire bottom side thereof located adjacent to the airfoil on which it is mounted and which constitutes the base member of a cantilever truss structure. The truss structure also includes a king-post rib 43 and a pair of diagonal truss means 44 and 45, extending forwardly and rearwardly, respectively, from the upper end of the king-post 43 and connected to the bulkhead 42 near its ends. The tip truss structure also includes forward and rearward end ribs 46 and 47, respectively, and a plurality of vertically extending intermediate ribs 50, all parallel to the king-post rib 43.

55 The center or king-post rib 43 (see Figs. 3

and 6) includes two spaced channel-shaped chord members 48 extending upwardly from opposite sides of the bulkhead 42 and converging toward each other at the upper ends. The chord members 48 are welded, respectively, to stiffening plates 51, the inner edges of which are offset to overlap as indicated at 53 in Fig. 6. The two plates 51 are joined by a tie-plate 54 welded to them adjacent their lapped edges.

As shown in Figs. 3 and 4, each diagonal truss means 44 or 45 comprises a pair of parallel channel-shaped members 44a and 44b or 45a and 45b, respectively. The diagonal members 44a and 45a adjacent one surface are welded at their upper ends, Figs. 6, 20 and 21, to brackets 57 which are welded to a gusset plate 58 which is in turn welded to the upper end of the king-post rib chord member 48. Likewise, the diagonal members 44b and 45b are welded to similar brackets 57 which are welded to a gusset plate 58 which in turn is welded to the other king-post rib chord member 48.

Referring to Figs. 23 and 24, each of the forwardly extending diagonal members 44a, 44b is connected to the bulkhead 42 and to the lower ends of the spaced chords of the forward rib 46 by gusset plates 61, the gusset plates each having a horizontal flange 62 welded to the bulkhead 42 and a vertical flange 63 welded to a chord member 66 of the front end rib 46. The rib chord members 66 project downwardly through the bulkhead 42 adjacent a transverse stiffening member 65 which is secured across the bottom face of the bulkhead 42. The forward end rib 46 is generally representative of the other vertically extending intermediate ribs 50 and the rear end rib 47. Figs. 4 and 5 illustrate another such rib, the same comprising a pair of Z-shaped chord members 66. In Fig. 7 the rear end rib 47 is shown.

Where the conformation of the tip structure is such that the marginal edge or tip bow 69 is relatively blunt, as in Fig. 4, the spaced upper ends of the rib chord members 66 are welded to a marginally flanged transverse nose plate 71 which is in turn welded through its flange to the tip bow 69. The rib chord members 66 are intermediate connected by a transverse channel member 73 or the like and at their lower ends extend through the web of the bulkhead 42. The projecting ends of the chord members 66 are attached through the medium of gusset plates 75 to the ends of channel-shaped stiffeners 65 which are welded to the outer face of and form a part of the bulkhead 42.

Fig. 6 shows a construction similar to that of Fig. 4, but of the king-post rib 43, and here the transverse nose plate 71 is welded through its marginal flange to the tip bow 69 and to the rib members 48 and 54.

Where the tip bow 69 is relatively sharp in section, as in Fig. 7, the rib chord members 66 overlap and are welded together and to an extension 77 of the transverse nose plate 71 which is in turn welded through its marginal flange to the tip bow 69.

The tip bow 69 intermediate adjacent ribs and intermediate the end ribs and the bulkhead 42 is closed in by rigidifying plates 72 having marginal side flanges 72a welded to the tip bow 69 and end flanges 72b welded to the adjacent nose plates 71.

Referring to Figs. 4 and 6, a skin blanket, which includes a cover or skin 82 and a plurality of flanged channel-shaped stiffeners or stringers 83

welded thereto, is secured to the ribs by channel-shaped clips 84 welded to the sides of the stiffeners 83 and to the rib chord members 66.

Referring to Figs. 14, 15, 16 and 17, the lower ends of the rearwardly extending diagonal members 45a and 45b forming the rear diagonal truss member 45, are each connected to an angularly bent gusset plate 85 which includes the backing plate 85a welded thereto, the gusset plates at the bottom of the structure being connected by two transverse U-shaped brackets 86 and 87 having flanges 88 at each end welded to the plates 85a of the opposite gusset plates 85. As shown in Fig. 15, the lower ends of these rib chords 66 are connected above the bulkhead 42 by a transverse strut member 14. The two rear ribs do not extend through the bulkhead lest they interfere with the action of the rudder.

Referring to Figs. 17, 18 and 19, the bottom webs of the U-shaped brackets 86, 87 are welded to the bulkhead 42, and a bearing supporting ring 91 is bolted to the lower face of the bulkhead by bolts 92 extending through the bulkhead and the U-shaped brackets. Roller bearing 93 is mounted in the bearing ring 91 to rotatably support the upper end of the rudder shaft 35.

Again referring to Fig. 1, the tip structure above described is adapted to form the tip of an airfoil such, for example, as the fin 31 on which it is mounted by connecting the king-post rib 43 of the tip structure to the main spar 33 of the fin, and by connecting the forward end rib 46 of the tip to the forward spar 32 of the fin.

As shown in Figs. 8 to 11, the main spar 33 of the fin structure is formed by chord members 101, only one of which is shown, which extend upwardly along the sides of the fin structure and which are connected by suitable transverse strut members. The upper transverse strut member 102 is channel-shaped, has a ridged reinforced web 103 and is welded to one wall of each chord 101 through an intervening Z-shaped gusset plate 104 extending upwardly above the edge of the fin structure where it is welded to the downwardly projecting end 105 of one of the chord members 48 of the king-post rib 43 of the cantilever tip structure.

A flanged transverse channel member 106 has one wing abutting and welded to the top wing of the transverse fin truss member 102, and the web thereof welded to the Z-shaped gusset plate 104, while its other wing is welded to the outermost wing of the transverse stiffening member 65 of the bulkhead 42. The fin structure is provided on each side at the top with a Z-shaped strengthening member 108 extending along the airfoil surface and transversely of the spar 33. The member 108 at each end (Figs. 9 and 11) is connected to a Z-shaped connecting plate 104 and also to one wing of the fin spar chord 101 by a bent bracket 109. An angularly bent chord member 111 of the tip bulkhead 42 has one flange welded to the lower edge of the blanket skin 82.

Referring to Figs. 1, 12 and 13, the forward anchorage of the diagonal truss member 44 of the tip is connected to the upper end of a forward spar 32 of the fin structure. At this point, an angle-shaped transverse fin spar strut member 113 connects the fin edge-strengthening members 108 at each side of the body. The rib chord members 66 of the forward end rib 46 of the tip extend downwardly through the bulkhead 42, as previously noted, and each is connected to a gusset plate 75 which is in turn welded to a gusset plate 115 secured to the vertical wing

of the angle member 113. The lower edge of the blanket skin 82 of the tip structure is here welded to the angularly bent chord member 111, as before. The skin 117 for the fin body is welded to the horizontal edge strengthening member 108. A cover finishing strip 119 is employed to close the space between the skins 82 and 117 of the tip and fin structure.

There is thus provided an airfoil tip structure which includes a cantilever truss construction, the main stress points of the base of the cantilever tip truss being immediately associated with the main stress points of the fin, that is, with the ends of the two spaced spars and the rudder shaft of the fin. The tip construction is also easy to fabricate and assemble, the ribs, skin blankets, bow tip, and bulkhead, each comprising one sub-assembly, which sub-assemblies may be welded together successively until finally the bulkhead is applied. Thereafter the entire tip assembly may conveniently be welded through companion projecting elements to the fin body and finally the skin finishing strips 119 applied.

The structure is such that assembly may be effected by the following procedure:

The tip bow is made as one sub-assembly, including the pre-shaped double-curved skin cover 69, the nose plates 71 with projecting ends, and the rigidifying closure plates 72.

The skin blankets and parti-ribs form two other sub-assemblies or half-shells, including for each half-shell a skin blanket composed of skin 82 and stiffeners or stringers 83 secured to rib chords 66, 48, 51, and connecting clips 84. The diagonals 44a, 45a form a part of one half-shell and the diagonals 44b, 45b form a part of the other half-shell assembly. To one of the half-shell assemblies one end of the struts 73 and one side of the splice plate 54 may be secured.

The other sub-assembly comprises the bulkhead sheet 42 having the illustrated lightening and access openings to which are secured the transverse rib struts 65, the marginal chord members 111, the interior rib strut 74, and the interior transverse bearing bracket struts 86, 87.

The tip bow sub-assembly is placed in a jig along with the half-shells and by reaching into the interior with suitable welding tongs the projecting ends of the tip bow nose plates are welded to the ends of the rib chords 66 and 48, and the rib chords such is in Fig. 7 which overlap are welded together. Also the unattached ends of the rib struts 73 are welded to the rib chords of the opposite half-shell and the other edge of the splice plate 54 is welded to the rib plate 51. Either before or after this assembly is made but before the bulkhead is placed the tip bow skin 69 is welded to the half-shell skins 82.

Then this bulkhead 42 is pushed into position and welded through the edge chord 111 to the skin sheets 82. By reaching through the access openings the struts 74, 86 and 87 are welded to the half-shell assembly. The bearing 91 is then secured by the bolts 92, though this may be done after the tip has been attached to the fin.

The tip is attached to the fin by welding through the mating flanges of the channels 65 and 106 (Fig. 10) and the parts 75, 115 (Fig. 13). Then the gap cover strips 119 are bolted in place, nuts having previously been secured inside the assembly in usual fashion.

Although I have described in detail one specific embodiment of this invention in connection with a specific type of airfoil structure, it will be apparent that such description is for the purposes

of illustration only and that the invention can be variously modified and adapted within the scope of the appended claims.

What is claimed is:

1. An airfoil structure comprising in combination, a stabilizer fin having a longitudinally extending spar, a tip structure for said fin having a bulkhead along the edge thereof adjacent said fin, a central rib forming a king-post connected to said bulkhead and extending between said bulkhead and the marginal edge of said tip, means connecting said king-post to the longitudinally extending spar of said fin, diagonal truss means connecting the outer end of said king-post with the bulkhead adjacent the opposite ends, said tip structure extending outwardly to form a cantilever support overhanging the trailing edge of said fin, and a shaft bearing positioned on the overhanging portion of said bulkhead and supported by the adjacent end of one of said diagonal truss means.

2. An airfoil structure comprising in combination, a stabilizer fin having spaced longitudinally extending spars, a tip structure for said fin having a bulkhead along the edge thereof adjacent said fin, a central rib forming a king-post connected to said bulkhead and extending between said bulkhead and the marginal edge of said tip, means connecting said king-post to one of the longitudinally extending spars of said fin, front and rear diagonal truss members connecting the outer end of said king-post with the bulkhead adjacent the opposite ends, means connecting a front diagonal truss member at said bulkhead to the other spar of said fin, said tip structure extending outwardly to form a cantilever support overhanging the trailing edge of said fin, and a shaft bearing positioned on the overhanging portion of said bulkhead and anchored to the adjacent end of one of said diagonal truss members.

3. An airfoil structure comprising in combination, a stabilizer fin having a longitudinally extending spar, a tip structure for said fin having a bulkhead along the edge adjacent said fin, a central rib in said tip structure forming a king-post connected to said bulkhead and extending between said bulkhead and the marginal edge of said tip, means connecting said king-post rib to said longitudinally extending spar comprising a frame member supported on said spar and extending transversely of said airfoil structure, a second frame member connected to said central rib and extending transversely of said tip structure and adapted to rest upon and be supported by said first-named frame member, and means for connecting said frame member to said spar.

4. An airfoil structure comprising in combination, a stabilizer fin having a longitudinally extending main spar, a second parallel forwardly located spar, a tip structure for said fin having a bulkhead along the edge thereof adjacent said fin, a central rib forming a king-post connected to said bulkhead and extending between said bulkhead and the marginal edge of said tip, means connecting said king-post rib to said main extending spar, forwardly and rearwardly extending diagonal truss members connecting the outer end of said king-post with the bulkhead adjacent the opposite ends, and means for anchoring the forward end of said forwardly extending truss member to the forwardly located spar.

5. An airfoil structure comprising in combination, a stabilizer fin having a longitudinally extending main spar, a second parallel forwardly

located spar, a tip structure for said fin having a bulkhead along the edge thereof adjacent said fin, a central rib forming a king-post connected to said bulkhead and extending between said bulkhead and the marginal edge of said tip, means connecting said king-post rib to said main spar, forwardly and rearwardly extending diagonal truss members connecting the outer end of said king-post with the bulkhead adjacent the opposite ends, and means for anchoring the forward end of said forwardly extending truss member to the forward vertical spar of said fin structure, including a rib in said tip structure, a gusset plate connected to the forward end of said truss member and to said rib and said bulkhead, and means connecting the projecting end of said rib to said forwardly located spar.

6. An airfoil structure comprising in combination, a main body portion, a tip sub-assembly secured to and forming an end extension on the main body, the body and tip comprising a frame and covering skin, the tip overhanging one edge of the main body and having on the overhang a bearing anchorage for hinging a movable airfoil.

7. An airfoil structure comprising in combination, a main body portion, a tip sub-assembly secured to and forming an end extension on the main body, the body and tip comprising a frame and covering skin, the tip overhanging one edge of the main body and having on the overhang a bearing anchorage for hinging a movable airfoil, the main body having a spar adjacent the side of the tip overhang, and the tip having a spar extension secured to the end of the spar and a diagonal brace from the upper part of the spar extension into the overhang near the bearing anchorage.

8. An airfoil structure comprising in combination, a main body portion, a tip sub-assembly secured to and forming an end extension on the main body, the body and tip comprising a frame and covering skin, the tip overhanging one edge of the main body and having on the overhang a

bearing anchorage for hinging a movable airfoil, the main body having a first spar adjacent the side of the tip overhang and a second spar on that side away from the overhang, and the tip having a spar extension secured to the end of the first spar and diagonal braces from the upper part of the spar extension to the region of the bearing anchorage and the region of the end of the second spar.

10. An airfoil structure comprising in combination, an airfoil body having spaced longitudinally extending spars, a tip structure secured to said body and having a bulkhead along the edge thereof adjacent the body, said tip including an intermediate rib forming a king-post connected to said bulkhead and extending between said bulkhead and the marginal edge of said tip, means connecting said king-post rib to one of said body spars, diagonal truss means connecting the outer end of said king-post with the bulkhead adjacent the opposite ends, and means connecting the bulkhead and tip at one end of the truss means on one side of the king-post to another body spar.

25. An airfoil structure comprising in combination, an airfoil body having spaced longitudinally extending spars, a tip structure secured to said body and having a bulkhead along the edge thereof adjacent the body, said tip including an intermediate rib forming a king-post connected to said bulkhead and extending between said bulkhead and the marginal edge of said tip, diagonal truss members connecting the outer end of said king-post with the bulkhead adjacent the opposite ends, and means connecting the tip at one end of one truss member to another spar of said body; said tip projecting outwardly to form a cantilever support overhanging the trailing edge of said airfoil body for an airfoil hinge, a 30 diagonal truss member being connected to the bulkhead at said hinge.

MICHAEL WATTER.
GEORGE W. PANCOE.
